FACSIMILE SCANNING AND CONTROL SYSTEM

Arthur C. Rustad, Floral Park, N. Y., assignor to
Press Wireless, Inc., New York, N. Y., a corpora-
tion of Delaware

Application July 31, 1946, Serial No. 687,481

12 Claims. (Cl. 178—69.5)

1

This invention relates to facsimile scanning machines and more particularly to a continuously operable scanning drum control arrangement for use in such machines.

In certain fields of facsimile use it is often necessary to make a large number of transmissions successively. In such cases when the sheet or film is insufficient to accommodate the entire transmission, it is usually necessary to remove the used paper or film from the scanning drum before transmission can proceed. This necessitates keeping the transmission equipment in a state of idleness until a new sheet of paper or film is wrapped on to the drum in place of the used one. An arrangement for overcoming this disadvantage is disclosed in application Serial No. 625,591, filed October 30, 1945.

It is another object of this invention to provide a phasing control circuit arrangement associated with the drive shaft of the scanning drum for starting the drums and providing for continuous scanning after the initial circuit adjustments.

A feature of this invention relates to the plural section scanning drum having successively operable drive controls whereby either section or both sections can be rotated for scanning and with a minimum of required phasing adjustments.

Another feature of this invention relates to the novel phasing and speed control arrangement employing a two-position switch and a novel combination of electron tubes.

A further feature of this invention relates to the novel organization, arrangement and interconnection of parts which cooperate to produce an improved facsimile scanning machine.

Other objects, features and advantages of this invention not particularly set forth will be apparent to those skilled in the art as will be evident in the following descriptions taken in connection with the accompanying drawing, in which:

Fig. 1 is a schematic block diagram of an arrangement employing this invention.

Fig. 2 is a cross-sectional view of the clutch drive arrangement shown in block form in Fig. 1.

Fig. 3 is a schematic diagram showing a mechanical arrangement for effecting operation of the desired drum section.

Fig. 4 is a view, partly in circuit diagram form and partly in block form, showing the phasing and speed control features of the invention.

A particular application of the phasing and motor control arrangement of this invention is

its use in conjunction with the plural drum scanning machine described in application Serial No. 625,591, filed October 30, 1945. Since the scanning drum is described in detail in that application, its description will be confined to that necessary for an understanding of this invention, and parts referred to in this application which are the same in construction and function as corresponding parts referred to in said application Serial No. 625,591, bear the same designation numerals in both applications.

Referring more particularly to Figs. 1 and 2, driven shaft 6 carries scanning drum sections 7 and 8 mounted thereon, shaft 6 being driven by synchronous motor 10 through clutch 80. Solenoid 52 is provided to operate clutch 80 in accordance with the setting of selector button switch 51. Drum section 8 is mounted in ball bearing races on shaft 6 and can be stopped without stopping the shaft 6, or it can be rotated while shaft 6 is stationary. Rotation of drum section 8 without reference to the rotation of shaft 6 is made possible by the provision of resilient but positive drive means between clutch 80 and drum section 8, as represented by the numeral 25. Drum section 7 is pinned to shaft 6 and rotates as a unit therewith. Sections 7 and 8 are of the same diameter and there is a minimum spacing between their adjacent ends in order that the two drum sections can be employed effectively as a single continuous drum surface if desired.

Clutch 80 is driven by worm drive 11 (Fig. 2) associated with motor 10. Worm drive 11 meshes with worm wheel 12, keyed to sleeve 13 which is rotatable with respect to shaft 6. Likewise, clutch plates 14 and 15 are keyed to sleeve 13. Shiftable clutch plates 16 and 22 are slidably keyed on the sleeves 17 and 21 respectively pinned to the shaft 6. Coil springs 20 and 24 cooperating with shiftable plates 16 and 22 respectively normally cause those plates to be held in driving engagement with clutch plates 14 and 15 to cause drum sections 7 and 8 to rotate as a unit. If shiftable plates 16 and 22 are declutched or out of driving engagement with plates 14 and 15, neither drum section can be rotated by them. If shiftable plate 22 is clutched with clutch plate 15 and slidable plate 16 is declutched from clutch plate 14, the worm 11 is disconnected from shaft 6 and that shaft and drum section 7 pinned thereto do not rotate but drum section 8 is rotated through the medium of the clutch plate 15, driving plate 22, which in turn causes rotation of the resilient positive drive means 25 coupled to section 8. Conversely, if slidable plate 22 is de-

clutched from plate 15 and slidable plate 16 is clutched with plate 14, the driving or rotation of shaft 6 and drum section 7 pinned thereto is effected while the driving engagement of section 8 is lost.

From the foregoing description, it is readily seen that the relationship of clutch 14 and 15 with the slidable clutch plates 16 and 22, determines whether rotation of motor 10 will effect rotation of neither drum section, both drum sections, or only one of the drum sections. Selector switch button 57 is set to control the desired rotation of the drum sections 7 and 8, and the subsequent operation of solenoid 52 causes the solenoid plunger 53 to effect the desired actual mechanical positioning of the elements of the clutch 80, whereupon motor 10 causes the rotation of drum sections 7 and 8 in accordance with the selector switch setting. The actual mechanical arrangement required to effect this operation is described in detail in the above referred to application and is shown in schematic form in Fig. 3.

Referring to Fig. 3, shiftable clutch members 16 and 22 are provided with suitable bifurcated clutch levers 29 and 28 respectively pivotally mounted at 65 on plate 30. Each bifurcated lever 28, 29, contains appropriate pins 31 and 32 which ride in the peripheral grooved face of the associated shiftable clutch member. The lower ends 39 of levers 28 and 29 engage arms 33 and 34 fastened to rocker shafts 35 and 36 respectively. Suitable contact rollers 37 and 38 at the end of arms 33 and 34 respectively are held in contact with the lower ends 39 by leaf springs 41 and 40 respectively. Members 43 and 42 attached to rocker arms 36 and 35 respectively also carry the rollers 41 and 46 for the purposes to be described. The members 43 and 42 also carry the latch members 44 and 45 which are so called because they are adapted to latch themselves underneath the magnet controlled bar 48. Bar 48 is supported at its ends by rollers 49 and 50 in roller guides 51 and 52a respectively which are rigidly fastened to the casting which houses solenoid 52. Members 54 and 55 attached to bar 48 engage the grooved portion of plunger 53 as shown.

Selector button 57, normally held in a raised position above plate 30 by spring 58, has a shank 59 which carries the semi-circular flat shoe 60. Shoe 60 is rotatable about the vertical axis of shank 59 and is arranged to depress either, both, or neither of the rollers 46 and 47, thereby effecting the desired selection for rotation of drum sections 7 and 8. To effect the desired selection, pin 61 of button 57 is rotated until it is aligned with the hole in plate 30 which corresponds to that selection, and then button 57 is depressed.

If it is desired to have neither drum section rotate when the motor rotates, pin 61 is aligned with hole 62 and depressed therein. Shoe 60 then overlies both rollers 46 and 47 and both latches 44 and 45 are depressed and latch themselves beneath bar 48 as shown in the dotted position. In this position, arms 33 and 34 are rotated inwardly causing levers 39 to be rotated against the force of springs 20 and 24 (Fig. 2) about their respective pivot 65, thereby declutching shaft 6 from the motor and preventing both the drum sections from being rotated. In this condition the film or sheet to be scanned is loaded on to the drums. Loading may be accomplished by wrapping a single sheet or film around both drums to form in effect a single continuous scan-

ning drum, or each drum may be wrapped separately to form two scanning drums. When the drums are loaded and the film or sheet secured thereon and the scanning head (not shown) correctly positioned and the necessary electrical adjustments made, the machine is in condition to begin operation.

Operation is started upon receipt of the starting pulse by solenoid 52 which causes plunger 53 to move upward causing bar 48 to unlock the latches 44 and 45 allowing slidable clutch members 16 and 22 to engage or clutch with clutch plates 14 and 15 respectively. As previously stated, the rotation of either drum section may be stopped by appropriately rotating and depressing button 57 to cause the pin 61 to engage the desired hole in plate 30. For example, if button 57 is depressed so as to cause shoe 60 to overlie only the roller 47, only the latch 45 latches bar 48. This causes a rocking only of shaft 36 and results in a declutching of shiftable member 16 from clutch plate 14 causing shaft 6 and drum section 7 to be stationary while engagement of clutch members 15 and 22 allows rotation of drum section 8 to continue.

Referring to Fig. 4, clutch 80 is shown in a side elevational view taken along the line 4-4 of Fig. 2. Commutator ring 81 of suitable insulating material is affixed around and rotatable with clutch plate 15. This commutator includes a short conducting segment 82, which cooperates with a carbon brush 83 fixedly mounted with respect to the commutator but contacting with the periphery thereof. The conducting segment 82 is imbedded in ring 81 and contacts with brush 83 during each revolution of the commutator, segment 82 being of such a length that it occupies approximately 18° of the commutator periphery.

The motor 10 is supplied with amplified current generated by turning fork oscillator 84 which operates, for example at 2400 C. P. S. This frequency is then subdivided in a suitable frequency subdivider of any well-known type, e.g., multi-vibrator 85, to convert the 2400 C. P. S. into a 480 C. P. S. signal, which is then applied to a keyer stage 86 which keys the 480 C. P. S. signal on and off as will be described. The keyed frequency is then further subdivided by multi-vibrator 87 to 60 C. P. S. which is amplified in amplifier 88.

The on and off keying of stage 86 is controlled by the cathode resistor 89 of a grid-controlled high mu triode 90, whose control grid receives a recurrent D. C. phasing impulse from the output of the amplifier rectifier 91 which during the phasing period is supplied from the transmitter 92 in the well-known manner. Resistor 89 is of such a value that with an increase of plate current through tube 90, produced by the received phasing impulse, the drop across resistor 89 applied to cathode 92a of tube 93, biases the latter tube to plate current cutoff. When tube 93 is thus cut off, no driving signal is applied to the multi-vibrator 87, which therefore generates its normal frequency of for example 57 C. P. S. When the signal from tube 93 is applied to multi-vibrator 87, the latter delivers a 60 C. P. S. signal. Thus, the speed of synchronous motor 10 can be controlled between 57 and 60 C. P. S. It will be clear therefore, that the received rectified phasing signal cannot cause cutoff of tube 93 so long as the resistor 89 is short-circuited. Consequently, as long as resistance 89 is not short-circuited, the received rectified phase impulse causes the motor 10 to lower its speed. Associated with com-

mutator 81 and tube 90 is a two-position stay-put switch 94, and a push-button switch 95, which is normally in the position shown. When switch 94 is in position #1, resistor 89 is normally short-circuited through the contact 96 of switch 95. On the other hand, when switch 95 is depressed, and assuming brush 83 is riding on the insulated portion of the commutator 81, the receipt of a phasing impulse from the transmitter draws sufficient plate current through resistor 89 to cause tube 93 to go to cutoff and causing the motor 10 to slow down. However, when the motor reaches a speed and phase at which the segment 82 contacts brush 83 coincidentally with the receipt of the phasing impulse from amplifier 91, this received phasing impulse is ineffective to cause cutoff bias on tube 93, and the motor 10 therefore continues to run at its normal speed of 60 C. P. S. under control of the tuning fork oscillator 84.

After the motor 10 and the drum shaft 6 have thus been properly phased with the transmitter, switch 94 is moved to position #2 and either of the drum sections can be started or stopped under control of solenoid 52 and the selector button 57 as above described. In order to effect starting of a particular drum section, the button 57 is turned so as to engage the shoe 60 with the proper roller 46 or 47 and the push-button 95 is operated. Thereupon, current flows from the positive terminal 97 of the D. C. power supply through the limiting resistor 98 and thence through the winding of solenoid 52 through switch 94 in position #2, through the arm and contact 99 of switch 95, brush 83 and segment 82 of commutator 81 to ground. As a result of the operation of solenoid 52, the selected one or both of the latch members 44 and 45 is operated under control of the bar 48 so as to operate the corresponding clutch member 16 or 22. In other words, the segment 82 not only serves the purpose of controlling the phasing but it also controls the application of the starting impulse to the clutch control solenoid 52. Thus, by means of push-button 57 and switch 95, either or both of the drums may be selectively started and stopped, it being understood that during the actual operation of the drums for facsimile recording, the phasing signal is not transmitted since the phasing operation is effected preliminarily to the actual transmission and reception of the picture signals. Thus, if the left-hand drum section 8 (Fig. 1) is in operation for actual scanning, the right-hand drum section 7 may be stationary for loading with another picture. When the loading of section 7 is completed, the push-button 95 can be operated and the button 57 turned so as to start the drum section 7 in scanning operation. The scanning head 68 which is operated by lead screw 66 is then allowed to progress towards the right until the right-hand drum section 7 is being scanned. During the scanning of the section 7, the left-hand drum section 8 may be stopped and reloaded and restarted in phase. No additional pulses are required nor is any time consumed between the drum loadings to effect the phasing.

While there has been here described a preferred embodiment, it is understood that various changes and modifications may be made therein without departing from the spirit and scope of the invention.

What is claimed is:

1. In a facsimile scanning system, scanning drum means divided into separate scanning drum

sections, means to drive said sections synchronously as a unit, means including a shiftable clutch having a rotatable clutch member for selectively stopping one drum section without stopping the other drum section, a phasing commutator having a conductive phasing segment rotatable with said clutch member, a brush arranged to contact with said segment, an electric motor for said driving means, said clutch and said commutator, a resistance for developing a motor control voltage in response to a received phasing impulse, and means including said segment and brush for short-circuiting said resistance in synchronism with the receipt of said phasing impulses.

2. In a facsimile scanning system, scanning drum means divided into a plurality of separate drum sections, a common drive shaft for said sections, clutches between said drive shaft and each of said sections, a phasing commutator driven in synchronism with said drive shaft, an electric motor for driving said shaft, a grid-controlled tube for controlling the frequency of the alternating current applied to said motor, another grid-controlled tube having a cathode load resistor, said other grid-controlled tube adapted to have its plate current controlled by received phasing impulses, a circuit connection for biasing said first tube to plate-current-cutoff in response to phasing voltages developed across said cathode load resistor, and means including said commutator for short-circuiting said cathode load resistor during a portion of each revolution of said drive shaft.

3. A facsimile scanning system comprising, a scanning drum, an electric motor for driving said drum, a grid-controlled tube whose plate current controls the speed of said motor, means for normally biasing said grid-controlled tube to plate-current-cutoff when said motor is running at the desired speed, another grid-controlled tube whose plate current is controlled by received phasing signals, connections between the said tubes so that the first tube is biased to plate-current-cutoff when phasing signals are applied to the grid of the second tube, and a commutator rotatable with said scanning drum for rendering the second tube ineffective to apply plate-current-cutoff bias to the first tube so long as the motor is driving said drum at synchronous speed.

4. A facsimile scanning system comprising, a scanning drum, a motor for driving said drum, a phasing commutator rotatable with said drum, said commutator having a phasing segment, a source of fixed frequency alternating current, a frequency converter for said fixed frequency, a grid-controlled tube for controlling the frequency converter to deliver to the motor an alternating current of different frequency from said fixed frequency, another grid-controlled tube for controlling the plate-current-cutoff bias of the first tube, means to apply received phasing signals to the control grid of said other tube, and means controlled jointly by said phasing signals and said commutator for selectively determining the application of plate-current-cutoff bias to said first tube.

5. A facsimile scanning system according to claim 4 in which said frequency converter delivers a lower frequency to said motor when said first tube is biased to plate-current-cutoff as compared with the frequency delivered to the motor when the said first tube is plate current conductive.

6. A phasing and speed control arrangement

for facsimile machines and the like comprising, an electric driving motor, a tuning fork oscillator, a first multivibrator controlled by said oscillator, a second multivibrator, said first multivibrator being connected to the control grid of said tube and said second multivibrator being connected to the plate of said tube, the output of said second multivibrator determining the speed of said motor, means effective when said motor is operating at synchronous speed for biasing said tube to pass plate current and thereby causing said second multivibrator to generate the normal synchronous frequency for said motor, and means responsive to received phasing impulses for biasing said tube to plate-current-cutoff and thereby causing said second multivibrator to supply a different frequency to said motor.

7. A system according to claim 6 in which said phasing signals are ineffective to cause said second multivibrator to apply said different frequency until the scanning drum is phased with the said received phasing impulses.

8. A system according to claim 6 in which the said means responsive to the received phasing impulses for controlling the cutoff bias on said tube comprises another grid-controlled tube and a commutator rotating in unison with said scanning drum.

9. A phasing and speed control arrangement according to claim 6 in which the means responsive to the received phasing impulses for controlling the plate conductivity of said grid-controlled tube comprises a second grid-controlled tube whose control grid is excited by the received phasing impulses, said second tube having a cathode load resistor which is connected to the cathode of the first tube and tending to bias the first tube to plate-current-cutoff as phasing impulses are received, and a commutator rotating in unison with the scanning drum for short-circuiting said cathode load resistor to prevent received phasing impulses from changing the motor speed when the scanning drum is in phase with a distant transmitter.

10. A facsimile synchronizing and phasing system comprising, a facsimile receiving drum to be phased with a distant transmitter under control of received phasing impulses, a grid-controlled tube for producing a D. C. biasing voltage in response to the received phasing signals, another grid-controlled tube whose grid is arranged to be biased to plate-current-cutoff under control of said voltage, a driving motor for said drum, a source of current for said motor whose frequency varies between two values in accordance with the plate current on and off condition of said second tube, a commutator rotatable with said drum and having contacts recurrently closed during the drum rotation for short-circuiting said bias voltage away from said second tube, and a manually-operable switch for controlling the said short-circuiting action of said commutator.

20 11. A facsimile synchronizing and phasing system according to claim 10 in which said second tube is normally plate current conductive and said source of current normally drives said motor at a synchronous speed when said drum is in phase with the transmitter, and means to lower the frequency of said source when said D. C. biasing voltage is produced in response to said phasing signals.

25 12. A facsimile synchronizing and phasing system comprising a facsimile receiving drum to be phased with a distant transmitter under control of received phasing impulses, a first grid-controlled tube having a load resistor across which a D. C. voltage is developed in response to received phasing impulses, a second grid-controlled tube having its grid arranged to be biased by the voltage developed across said load resistor, a commutator rotatable with said drum, and means responsive to the coaction of the received phasing impulses and said commutator for short-circuiting said load resistor when said drum is in phase with the transmitter.

ARTHUR C. RUSTAD.
